UNITED STATES PATENT OFFICE.

JONAS B. BAIR, OF SANDBORN, INDIANA.

WASHING-MACHINE.

1,121,450.

Specification of Letters Patent. Patented Dec. 15, 1914.

Application filed July 29, 1911. Serial No. 641,291.

To all whom it may concern:

Be it known that I, JONAS B. BAIR, a citizen of the United States, residing at Sandborn, in the county of Knox and State of Indiana, have invented a new and useful Washing-Machine; and I do hereby declare the following to be a full, clear, and exact description of the invention such as will enable others skilled in the art to which it appertains to make and use the same.

This invention relates to a new and useful washing machine.

The invention in its broadest scope aims as its primary object, to provide a washing machine, including a pair of levers, connected at their ends to the plunger rods, and crossing one another approximately at their central portions and pivoted to a single post. The levers have connections with the single crank shaft for oscillating the same, which in turn reciprocates the plunger rods including their plungers.

A feature of the invention is the provision of a novel form of plunger, which is approximately triangular in cross section and hollow, and provided with a flange, which renders the plungers approximately dished, so as to cup and pound the clothes.

The drawing discloses only one form of the present invention, but in practical fields this form may require certain alterations, to which the patentee is entitled, provided the alterations are comprehended in the scope of what is claimed.

The invention comprises further features and combination of parts as hereinafter set forth, shown in the drawings and claimed.

In the drawings:—

Figure 1 is a view in side elevation of a washing machine, embodying the features of the invention. Fig. 2 is a plan view. Fig. 3 is a sectional view on line 3—3 of Fig. 2. Fig. 4 is a detail view of one of the plungers. Fig. 5 is a sectional view through the plunger rod. Fig. 6 is a detail view of a modified form of the plunger.

Referring to the drawings 1 designates the tub or receptacle, in which the clothes and the suds are placed. Hinged to the tub or receptacle as at 2 is a lid 3, having a central post or standard 4. Rising vertically from the lid and adjacent the hinged portion of the lid are two standards 5. In bearings of the standards 5 a crank shaft 6 having crank portions 7 is journaled. A

brace 8 connects the two standards 5. Journaled on one end of the crank shaft is a hand wheel 9 including a handle 10, whereby motion can be imparted to the crank shaft. Connecting with the crank 7 of the shaft are links 11, which in turn are connected to similar links 12 by the eyes 13, there being nuts threaded upon the links 12 on each side of eyes, for holding the links 11 and 12 in their relative position. The links 12 are pivotally connected to one end of each of the crossing levers 14, as at 15. At the point where the levers cross, they are pivoted upon separate pivots 16 on the post 4, as shown in Figs. 1 and 2. The post 4 forms a part of the base plate 17 which is bolted or otherwise secured at 18 to the lid 3.

Pivoted adjacent the free ends of the crossing levers as at 19 are plunger rods 20, which penetrate the lid 3 of the tub or receptacle 1, as is shown in the sectional view. The plunger rods 20 are provided at their lower ends with plungers or pounders 21. These plungers or pounders are constructed of sheet metal, and are hollow as shown. The bottoms 22 of the plungers or pounders are surrounded by flanges 23, thus rendering the plungers cupped or dished, as shown, so that when the plungers are reciprocated the clothes may be cupped and pounded, and when pounded, a vacuum is produced in the dished or cupped portions of the plungers, thus drawing and forcing the dirt from the clothes. The plungers or pounders are connected to the plunger rods, so as to have a slight swivelled sway or motion, so that the pounders or plungers will not strike the clothes at the same place. Incidentally a wringer 24, is erected on the washing machine, the purpose of which is apparent.

In Fig. 6 a different form of plunger or pounder 26 is shown, which may be substituted for those shown in Fig. 3.

As the crank shaft is rotated, the crossing levers or walking beams are oscillated on their independent pivots, which in turn operate the plunger rods and their respective plungers. As the plungers are reciprocated vertically the suds or other cleaning substance are forced and drawn through the clothes, which removes the dirt.

From the foregoing it will be evident that there has been produced a simple, novel and efficient washing machine, and one which

has not only been found to be practicable, but one which will save a great deal of labor.

The invention having been set forth, what 5 is claimed as new and useful is:—

In a washing machine, a tub, a lid, a post 10 detachably connected to and upstanding from the center of the lid, connected standards fixedly attached to and extending from the lid adjacent the periphery thereof, a shaft journaled in the standards and having spaced cranks extending in the same direction from the shaft, crossed upper and lower levers centrally fulcrumed upon the posts 15 and disposed in planes substantially at right angles to each other, a pounder con-

nected to each end of each lever, links pivotally connected to the levers and extending upwardly therefrom, and links pivotally connected to the respective cranks and 20 swiveled on the first named links, said lid being hingedly connected to the tub and adapted to swing relative thereto with the post, standards and the parts mounted thereon.

In testimony whereof I have signed my name to this specification in the presence of 25 two subscribing witnesses.

JONAS B. BAIR.
